UNITED STATES PATENT OFFICE.

JOHN B. GLOWACKI, OF CHICAGO, ILLINOIS.

RENEWABLE FUSE.

Application filed July 21, 1919, Serial No. 312,340. Renewed April 25, 1923.

To all whom it may concern:

Be it known that I, JOHN B. GLOWACKI, a subject of the Republic of Poland, having declared my intention to become a citizen of the United States, and a resident of the city of Chicago, in the county of Cook and State of Illinois, have invented certain new and useful Improvements in a Renewable Fuse; and I do hereby declare that the following 10 is a full, clear, and exact description of the same, reference being had to the accompanying drawings, and to the numerals of reference marked thereon, which form a part of this specification.

15 This invention relates to fuses, more particularly those employing a cartridge containing a strip of readily fusible metal.

Heretofore in fuses of this type the replacement of the fuse link in the cartridge 20 has been a difficult operation.

The principal object, therefore, of the present invention is to provide a simple, inexpensive fuse cartridge from which the fuse link may be readily removed and replaced without the use of tools.

Other and further important objects of this invention will be apparent from the disclosures in the specification and drawings.

25 The invention (in a preferred form) is illustrated in the drawings and hereinafter more fully described.

On the drawings:

Figure 1 is a side view of a fuse and a support therefor embodying the features of the present invention.

Figure 2 is an end view of the same.

Figure 3 is a longitudinal central section through the fuse cartridge with parts in elevation.

Figure 4 is a section on the line 4—4 of Figure 3.

Figure 5 is an end view of the fuse cartridge.

45 Figure 6 is a section on the line 6—6 of Figure 4.

Figure 7 is a plan view of the fuse link. As shown in the drawings:

The fuse cartridge 1 is shown supported by a pair of spring contacts 2 mounted on a suitable base 3. These contacts may be connected to the source of current in any desired manner.

The construction of the cartridge 1 is shown more particularly in Figure 3. A tube 4, preferably of insulating material such as

fibre or other suitable material, conveniently forms the body of the cartridge case. To one end of this tube a centrally apertured cap 5 is secured by any suitable means such as by punching a portion 6 of the cap into the periphery of the tube 4.

At the other end of the tube a ferrule 7 is mounted. The outer end of this ferrule is reduced in diameter so that a centrally apertured cap 8 of the same diameter as the inner end of the ferrule may have threaded engagement therewith.

The fuse element, shown more particularly in Figure 4, may conveniently consist of a cylinder 9 of non-conducting material such as fibre, with a metallic cap 10 secured to each end. Preferably each cap is provided with a central boss 13 adapted to pass through the aperture in one or other of the caps 5 and 8.

Along one side of the cylinder 9 is arranged a suitable fuse link 11, with its ends clamped to the caps 10 by means of split rings 12.

The parts of the cartridge and fuse element carried thereby are so proportioned that the distance between the shoulders of the caps 10 is slightly greater than the distance between the inner faces of the caps 5 and 8 when the latter is screwed home so that the caps 5 and 8 may be pressed firmly against the caps 10 to provide good electrical contact therewith and hold the same firmly in place.

I employ a fuse link made of composition metal having a series of sections of reduced width, as shown in Figure 7. In the cylinder 9 grooves 15 are provided adapted to register with the sections 14 of the fusible link and thereby provide ample air space therearound. Of course, it is obvious that the fusible link may be made in various sizes and metal compositions so that it may be adapted for use with different currents and under varying conditions.

The operation is as follows:

To replace a fuse link in the cartridge 1, the latter is pulled out of engagement with the spring contacts 2 and the cap 8 screwed off. This releases the fuse element, which is then free to drop out. Next the split rings 12 are removed to release the ends of the blown fuse link. A new fuse link is then laid along the cylinder 9 with its sections 14 of reduced width in register with the grooves 15 of the cylinder. The split rings

are slipped over the ends of the fuse link and the fuse element is then ready for reinsertion in the cartridge.

It should be observed that if the rings 12 are allowed to project beyond the ends of the caps 10, they will be pushed into place when the fuse element is placed within the cartridge and the cap 8 screwed into position. Obviously a plain strip fuse may be employed, however, the form shown in the drawings is preferred.

I am aware that numerous details of construction may be varied through a wide range without departing from the principles of this invention, and I therefore do not purpose limiting the patent granted otherwise than necessitated by the prior art and the annexed claims.

I claim as my invention:

- 20 1. A renewable fuse comprising in combination a tube of insulating material, a fuse holder within the tube having metallic end pieces comprising clamps, contact members at each end of said tube, one of said members being adjustable longitudinally of the tube to clamp the fuse holder between said members and maintain electrical contact between said end pieces and said members.
- 25 2. A renewable fuse comprising in combination a fuse holder having metallic end pieces comprising clamps, and a pair of contact members adapted to be brought toward each other to grip the fuse holder

therebetween and maintain electrical contact between said end pieces and said members.

3. A renewable fuse comprising in combination a tube of insulating material, an apertured cap secured to one end of the tube, 40 a metallic apertured cap having threaded engagement with a ferrule fixed to the other end of the tube, a fuse holder having end pieces adapted to contact electrically with said caps, and central lugs on said end pieces 45 adapted to extend through said apertures.

4. In a fuse device, a cylindrical insulating member, a conducting cap on each end of said member, split rings, one clasping each of said caps, an insulating housing surrounding said cylinder and caps, and end pieces on said housing connected to said caps.

5. In a fuse device, a cylindrical insulating member, a conducting cap on each end 55 of said member, split rings, one clasping each of said caps, a fuse clamped at each end by said rings, an insulating housing surrounding said cylinder and caps, and end pieces on said housing connected to said 60 caps.

In testimony whereof I have hereunto subscribed my name in the presence of two subscribing witnesses.

JOHN B. GLOWACKI.
